UNITED STATES PATENT OFFICE.

MAURICE STRANSKY, OF MOUNT VERNON, NEW YORK.

DESIGN FOR A HANGER OR SIMILAR ARTICLE.

45,315.

Specification for Design.

Patented Feb. 24, 1914.

Application filed November 16, 1912. Serial No. 731,877. Term of patent 7 years.

To all whom it may concern:

Be it known that I, MAURICE STRANSKY, a citizen of the United States, residing at Mount Vernon, in the county of Westchester and State of New York, have invented a new, original, and ornamental Design for a Hanger or Similar Article, of which the following is a specification, reference being had to the accompanying drawings, forming a part thereof, and in which—

I claim:

The ornamental design for a hanger or similar article, as shown.

MAURICE STRANSKY.
